UNITED STATES PATENT OFFICE.

ERNEST J. TURNER, OF PITTSBURGH, PENNSYLVANIA.

HOT TOP.

Application filed March 2, 1926. Serial No. 91,782.

The present invention relates broadly to the art of metal founding, and more particularly to so-called hot tops or feeders for use with standard ingot molds to improve the character of the ingots formed therein. At the present time it is customary in the art to which the present invention relates to utilize hot tops or feeders with ingot molds for the purpose of maintaining a body of molten metal available for feeding the shrinkage and thereby decrease segregation and piping. Actual experience has demonstrated the fact that hot tops applied to ingot molds insure the production of ingots free from defects throughout substantially the entire length of the ingot, the defects being limited to the crop end of the ingot.

Hot tops are ordinarily constructed of refractory material, such as fire clay, slag, cinders or the like, although it has been proposed to construct them of combustible or partly combustible or slow burning materials, and such hot tops have actually been used. The present invention is adaptable to hot tops of any desired composition or construction having any desired type of supporting means, and whether coated with water-proofing or fusible compounds or not, and whether of cellular or solid nature.

The major portion of ingot molds in use today are of such size that hot tops can conveniently be constructed and shipped in one piece without undue expense. As the size of the ingot molds increases beyond a certain amount, the cost of manufacturing hot tops in one piece increases out of proportion to the increase in the size of the mold, and the shipping of such hot tops without a high percentage of breakage becomes almost impossible.

Such large hot tops are also difficult to handle and apply to the molds, and their manufacture requires a special die for each size whether the size represents a multiple of smaller standard sizes or not.

The present invention has for one of its objects the obviating for the difficulties and objections referred to with respect to manufacture, cost, breakage and handling, and to provide units adaptable for use as such on smaller ingot molds, or adaptable for use in pairs on larger ingot molds.

Another object of the invention is to provide an improved unit structure of such na-

ture that necessary strength is provided during shipment and handling, while permitting expeditious change in the number of side walls whereby pairing of the units to provide a large hot top having an unobstructed pouring opening is made feasible.

In the accompanying drawings there are shown, for purposes of illustration only, certain preferred embodiments of the present invention, it being understood that the drawings do not define the limits of my invention as changes in the construction and operation disclosed therein may be made without departing either from the spirit of the invention or the scope of my broader claims.

In the drawings—

Figure 1 is a top plan view of one form of unit constructed in accordance with the present invention;

Figure 2 is a side elevation of the unit shown in Figure 1;

Figure 3 is a top plan view illustrating the contour of a mold cavity having a pair of units as shown in Figure 1 in operative position therein ready for the pour;

Figure 4 is a view similar to Figure 1 showing a slightly different embodiment of the invention;

Figure 5 is a top plan view of a pair of units of special construction to permit interlocking or inter-engagement thereof, and

Figure 6 is a view similar to Figure 5 showing a slightly different form of the invention.

In carrying out the present invention there may be constructed a plurality of hollow units as illustrated in Figures 1 and 2 of the drawings, each comprising side walls 3 and 4 of a contour, configuration and dimensions as required by a particular mold, it being understood that it is customary practice to so dimension the hot tops as to provide clearance between the walls thereof and the surface of the mold cavity, and to so shape the same as to substantially conform to the contour of the mold cavity.

The walls may be of any desired height determined in known manner by the molds with which they are to be used, and the walls 3 may each be provided with suitable means 5 such as ribs, shoulders, projections or the like, adapted to cooperate with the upper end of an ingot mold to limit the ex-

tent of projection of the hot tops into the mold and effect predeterminate position of the hot tops, as understood in the art. Preferably, the walls 4 are devoid of supporting means, although such means may be formed thereon if desired. The walls 4 are also conveniently formed with opposed grooves or scorings 6 adjacent the plane of juncture of the walls 3 and 4, to provide predeterminate cleavage lines facilitating breaking out of the walls 4 should such action be desired, as hereinafter more fully pointed out.

It will be understood by those skilled in the art that a hot top of the character described may be used in its entirety as a complete hot top. Assuming that the hot top has outside dimensions, not including the supporting means, of 19 by 17 inches, it might be used, for example, with an ingot mold having a cavity of approximately 20 by 18 inches.

It not infrequently happens, however, that it may be desired to use a hot top with a mold having a cavity of 41 by 18 inches. Heretofore it has been customary to construct one piece hot tops of a size suitable for such molds, notwithstanding the difficulties and objections before referred to.

In accordance with the present invention, the necessity of such a one piece construction is obviated without incurring any of the difficulties which have been involved in the use of four or more slabs or sections as heretofore proposed and attempted. In Figure 3 of the drawings there is shown the outline 7 of an ingot mold cavity having, for example, the approximate dimensions last given. The hot top for the mold is illustrated as comprising a pair of units as shown in Figures 1 and 2, each unit, however, having its wall 4 broken away to provide an unobstructed pouring opening for the molten metal. The ends of the side walls 3 abut along the lines 8 to prevent the escape of the molten metal, while the supporting means 5 maintains the U-shaped units in position.

It has been found in actual practice that a multi or two-unit hot top of the nature described is extremely advantageous. The two units can be constructed at a cost a great deal less than the cost of a one piece hot top, and they can be much more easily shipped and handled without nearly the percentage of breakage involved in one piece constructions. The cleavage lines enable accurate breaking as required without danger of breaking the remainder of the hot top. Without the temporary reinforcing walls 4, shipping of the hot tops without breakage becomes almost impossible due to the amount of overhang of the sides without any strengthening or supporting means.

In Figure 4 of the drawings there is illus-

trated a slightly different form of unit in which, however, parts corresponding to parts heretofore described are designed by the same reference characters heretofore used but having a prime applied thereto. The wall 4' is shown as having not only the scorings 6' located as before described, but also as having additional scorings 9 providing a cleavage line through an intermediate portion of the wall 4'. Such an arrangement has been found desirable with certain compositions, as well as with units of larger dimensions. The unit of Figure 4 may have outside dimensions, not including the supporting means 5', of approximately 26 by 21 inches whereby it is adapted for use as shown with an ingot mold having a cavity of slightly larger size, or is adapted for use as one of two units in a mold having a cavity approximately 53 by 22 inches.

It will be understood that in all cases the dimensions are illustrative only, and not definitely of limitations with respect either to unit sizes or mold sizes.

In some cases I have found it desirable to provide means on the ends of the side walls whereby units when used in pairs may be interlocked or inter-engaged along the lines of engagement. In Figures 5 and 6 there are shown slightly modified embodiments of the invention of such nature as to provide cooperation of the nature described. In Figure 5 the side walls are shown as having, respectively, a depression 10 and a projection 11, whereby when units of the same construction are reversed end for end, the projections will engage the depressions to hold the assembled units against relative lateral movement. In Figure 5 there are illustrated two units of identical construction reversed end for end and in adjacent positions.

If desired, the units may be of different constructions as illustrated in Figure 6, in which the unit A has projections 12 on the side walls, while the unit B has cooperating depressions 13. In the different figures the depressions and projections, respectively, are illustrated as of different shapes, but it will be understood that any desired shape may be used with any desired unit, the drawings being illustrative only of an expeditious manner of preventing relative lateral movement of assembled units.

Certain advantages of the present invention arise from the provision of a hot top unit adaptable for use as such, or adaptable for use in pairs with large molds.

Other advantages arise from the provision of a hot top unit having one side of such construction as to permit breaking away thereof at will, while effective for strengthening the unit when in position therein.

Still further advantages of the invention arise from the provision of a hot top of two

U-shaped sections and from the provision of means preventing relative lateral movement of the assembled sections.

I claim:

- 5 1. As an article of manufacture, a hollow hot top having continuous sides with supporting means on some of its sides terminating above its lower edge, one of its sides being free of supporting means to permit
- 10 two such hot tops to be placed in a mold with their adjacent sides in contact with each other.
- 15 2. As an article of manufacture, a hollow hot top having continuous sides with supporting means on some of its sides terminating above its lower edge, one of its sides being arranged to cooperate with a similar side of another hot top to form a hot top for a larger mold.
- 20 3. As an article of manufacture, a hollow hot top having continuous sides with supporting means on some of its sides terminating above its lower edge, one of its sides being arranged to cooperate with a similar side of another hot top to form a hot top for a
- 25 larger mold.

larger mold, said side being constructed to facilitate removal thereof.

4. As an article of manufacture, a hollow hot top having continuous sides with supporting means on some of its sides terminating above its lower edge, one of its sides being arranged to cooperate and interlock with a similar side of another hot top to form a hot top for a larger mold.

5. As an article of manufacture, a hollow hot top having continuous sides with supporting means on some of its sides terminating above its lower edge, one of its sides being free of supporting means to permit two such hot tops to be placed in a mold with 40 their adjacent sides in contact with each other, and interlocking means on the side free from supporting means arranged to cooperate with interlocking means on a similar side of another hot top when two hot 45 tops are used in a single mold.

In testimony whereof I have hereunto set my hand.

ERNEST J. TURNER.

CERTIFICATE OF CORRECTION.

Patent No. 1,666,759.

Granted April 17, 1928, to

ERNEST J. TURNER.

It is hereby certified that error appears in the printed specification of the above numbered patent requiring correction as follows: Page 2, line 68, for the word "designed" read "designated", and line 88, for the word "definitely" read "definitive"; and that the said Letters Patent should be read with these corrections therein that the same may conform to the record of the case in the Patent Office.

Signed and sealed this 8th day of May, A. D. 1928.
